CLAIM

The ornamental design for a dog training dummy, as shown and described.

DESCRIPTION

FIG. 1 is a front perspective view of a dog training dummy; FIG. 2 is a rear perspective view thereof; FIG. 3 is a right side view thereof, the left side being a mirror image thereof; FIG. 4 is a top view thereof, the bottom view being a mirror image thereof; FIG. 5 is a front elevation view thereof; and, FIG. 6 is a rear elevation view thereof. The broken lines in the drawings illustrate environmental structure that forms no part of the claimed design.
